TO HANDLEY-BROWN HEATER COMPANY, OF JACKSON, MICHIGAN, A CORPORA-
TION OF MICHIGAN.

FLUID-HEATING DEVICE AND METHOD OF OPERATING SAME.

Application filed April 19, 1926. Serial No. 103,174.

Our invention relates to a fluid heating device and method of operating the same. It relates particularly to the use of gas as a heating medium, and has to do with the provision of a novel and efficacious means for transferring the heating units to the fluid to be heated, whereby the fluid is maintained at an approximately uniform temperature with a relatively low rate of gas consumption and a minimum total consumption of gas.

In the past, various methods and means have been used for heating fluids, where the fluid is received in a suitable container in a cold state to be subsequently heated and transmitted for various uses, some of which have involved the application of a heating medium directly to the base of the container, some of which have contemplated the passing of fluid through a series of coils to present a large and quick acting heating surface, and others of which have passed the heating medium or gases through conduits positioned within the fluid container. These efforts at fluid heating have been numerous and quite varied, but the satisfactory and efficient results have not been obtained with reference to either efficient exchange of the heat units or efficient, low and constant rate of fuel consumption.

These efforts in the past have apparently failed because, for one reason, they have failed to properly pass the heating medium through or in contact with the liquid in the container in such a manner and at such a rate as to transfer a large portion of the heat units to the liquid. In other words, the attempts have generally been directed primarily to the heating of the water or liquid in hot water tanks or similar receptacles either quickly or by a large amount of fuel at infrequent intervals, and secondarily, to the utilization of substantially all the heat units and the application of a low rate of fuel at constant or frequent intervals. Another probable reason is that the rate of flow of the fuel or gas has heretofore been immaterial or not considered, whereby a large number of heaters have attempted to obtain efficiency by simply heating the fluid when desired or at intermittent intervals, with the use of a relatively large fuel or gas consumption.

Our invention contemplates the introduc-

tion of the heating medium or heating gases into the liquid container in such a manner that the heat units are given up gradually and substantially completely to the liquid within the container, and all unnecessary draft through the flue is avoided. Furthermore, by our device the burner is operated at a relatively low rate of fuel consumption at all times, whereby sufficient hot liquid is available at all times, whenever desired, with little appreciable increase in the rate of gas consumption.

More specifically, we have found that by passing the heating gases throughout the length of the heater or container, whereby the gases will uniformly and completely give up their heat units to heat the liquid, that the liquid within the container or heater may be uniformly and constantly maintained at the desired temperature, with a very small amount and rate of fuel consumption. Therefore, we preferably provide a container of relatively long cylindrical dimensions, in which is positioned a flue or conduit whose length is very great as compared to its cross section, and which conduit extends the length of the container and returns to a position as low or lower than the intake. A relatively small gas burner is placed at the entrance of this conduit, and a thermostat for controlling the amount of gas admitted to the burner is positioned in the bottom of the container adjacent the entrance for the cold water or fluid. The cold water inlet is arranged in a novel manner with respect to the heating conduits and the thermostat, whereby the admission of the gas is accurately and instantly controlled.

A low consumption burner is a great advantage to gas companies for the reason that it permits cutting down the size of the gas mains, and tends to eliminate peak loads at certain times of the day. By our arrangement of heating apparatus, the movement of the gases in the heating conduit is reduced to a minimum, whereby only a relatively small low consumption burner is required and utilized to keep the fluid in the container at the required temperature.

In the drawings:

Fig. 1 is a vertical longitudinal section through a hot water heating tank embodying the features of our invention and showing

the form and arrangement of the conduit for conducting the heating gases within and through the tank.

Fig. 2 is a vertical sectional view taken at 5 right angles to the section of Fig. 1 and showing the preferred manner of positioning the thermostat with respect to the cold water inlet and the heating gas conduit.

Fig. 3 is a horizontal cross section through 10 a tank, similar to Figs. 1 and 2, but showing a slightly modified form wherein two separate heating gas conducting conduits are utilized instead of one.

This invention is particularly adapted to 15 the heating of water in what is known as the storage type of hot water heater, but it will be understood that it is equally applicable to the efficient heating of water or other fluids in other types of containers. The invention 20 is illustrated in combination with the standard type of domestic hot water heater of general cylindrical shape, and of a length relatively long with respect to its cross section.

The outer shell of this tank may be designated 1, and may consist of sheet steel of suitable gage. A second shell 2 is centrally positioned within the outer shell, and a space between the two shells is filled up with, or carries a suitable insulating material 3.

30 Designed to be centrally positioned within the inner shell 2 is a U-shaped tubing 4, both legs of which extend through the bottom of the tank and the upper closed end of which reaches approximately to the top of the inner shell. This tubing or conduit is of relatively small cross section with respect to its length, and is preferably of the same diameter throughout. As shown in Fig. 2 the tubing is positioned centrally of the tank, and as 35 shown in Fig. 1 the two legs spaced equi-distantly from the walls of the tank. This positioning, size and arrangement of the tubing 4, for conducting the heated gases is a very important feature of our invention, as 40 it makes possible a maximum of efficiency in transforming the heat units from the heated gases to the water, and also makes possible the construction of a compact heating tank of extreme simplicity.

50 The intake 5 of the conduit 4 extends only a short distance below the bottom of the tank, and is adapted to receive the upper end of a suitable, single, low consumption burner 6. This burner is positioned adjacent the inlet 55 opening of the conduit 5 in any suitable manner, whereby the relatively small flame emanating therefrom is confined practically entirely within the lower end of such conduit.

The other leg 7 of this tubing or conduit 4 is 60 adapted to conduct the cooled exhaust gases away from the heater and preferably extends through the bottom of the tank and downwardly to a position below the bottom of the intake leg 5. The lower end of this exhaust 65 gas conduit 7 may be, if desired, connected

to a suitable flue by means of an interconnecting moisture trap 8. However, such an exhaust flue is unnecessary in the present construction because of the extremely low rate of gas consumption, and the arrangement of the 70 hot gas conduit within the tank. Hence it will be obvious that the tank may be placed anywhere in the basement or building without a chimney connection at all.

The cold water inlet to the tank is preferably by means of a suitable pipe 9, which extends downwardly through the top of the tank and approximately centrally thereof, as clearly shown in Figs. 1 and 2. This pipe extends the length of the tank and terminates 75 at a point near the bottom of the tank, and preferably between the inlet and outlet legs 5 and 7 of the conduit 4.

A thermostat couple 10, forming a part of a suitable thermostat 11, extends inwardly 80 transversely and centrally of the tank and in its preferred location projects between the conduit legs 5 and 7 and is positioned slightly below the lower end of the water pipe 9. The thermostat 11 may be of any standard type, 90 containing a suitable valve actuated by the relative expansion of the couple to control the rate of flow of the gas to the burner. A suitable valve 12 may be inserted between the thermostat 11 and the burner 6 making it 95 possible to control the maximum amount of gas to be supplied to the burner at any time. A suitable drip pan 13 may be positioned below the moisture trap and supported by the legs of the tank. A hot water outlet pipe 14 100 is positioned in the top of the tank, as clearly shown in Fig. 2.

It will be understood that although the U-shaped conduit 4 may be of any desired relative size in cross section, in the present heating apparatus and method of heat transfer, the conduit 4 is of relatively small cross section in proportion to its length, and in about the proportions as illustrated in the drawings. Therefore, instead of enlarging the 105 heating flue for use in tanks of larger capacity, it is preferable to provide a plurality of tubes 4, and burners, as illustrated in Fig. 3. Where two or more separate conduits are used they are preferably located centrally 110 and symmetrically with reference to the circumference of the heater, and the cold water inlet pipe is preferably positioned centrally of the legs of the conduits. The thermostat couple is also preferably positioned centrally 115 of the heating gas flues as well as at a point adjacent the bottom of the cold water inlet.

In operation, the incoming cold water having affected the thermostat to open the gas valve, the flame issuing from the single small burner is changed from a suitable pilot light to a flame sufficient to cause heat transfer and the raising of the temperature of the water within the tank. This burner flame, due to 120 the arrangement of the heating flue and 125 130

method of conducting the gases, is designed to operate at a relatively low rate of gas consumption, approximately 6 cubic feet per hour, as compared with an average of about 5 40 cubic feet per hour on other storage type heaters. A range of from 3 cubic feet to 15 cubic feet per hour will give measurably good results—and be a low consumption burner. The hot gases rising in the small 10 straight sided leg 5 of the conduit gradually and progressively impart their heat units to the water in the tank or boiler, the rate of transfer of heat units gradually diminishing as the gases approach the top or curve of the 15 conduit. By the time the gases have passed through the length of the relatively long flue and approach the lower end of the exhaust conduit, which is positioned beneath the intake of the inlet conduit, there has been a 20 maximum exchange of heat units whereby the temperature of the exhaust gases will be approximately the same or only slightly higher than the temperature of the tank.

Due to the novel arrangement of the intake and exhaust flues, the positioning of the inlet water pipe and thermostat, and the passing of the gases in the relatively small column from the bottom to the top of the tank and return, it is possible to maintain the temperature 30 of the water at the top and bottom of the tank approximately constant. In actual practice, under normal conditions, it is possible to maintain the water at the top at a temperature of about 150° F., and the temperature at the bottom of the tank at about 35 140° F. Due to this relatively long column of restricted cross section, the use of a low consumption burner, and the maintaining of the temperature approximately constant at 40 the bottom and top of the tank, the movement of the gases through the tube is reduced to a minimum and the gases travel at an extremely low but positive rate to thereby give up all of their heat units to the water within 45 the tank. When the water has reached the desired temperature the thermostat will be affected to restrict the flow of gas to the burner and the burner flame will be only such as to compensate for the loss by radiation.

50 It will thus be seen that we have provided a novel gas water heater of the storage type of an extremely simple, compact and inexpensive construction, and which heater may be operated to supply hot water at the desired 55 temperature at all times and with only a relatively small amount of gas or fuel and at a relatively low and approximately constant rate of consumption. It will further be seen that use of a low consumption burner of this 60 type, makes it possible for the gas company to solve some of their greatest present day problems in that such a burner permits the material reduction of the size of gas mains and also tends to eliminate peak loads at certain 65 times of the day.

We may add that a great success of our unit is, in our judgment, due to the practical elimination of excess ventilation or draft through the long, narrow, inverted, U-like flue. In the types of center flues that are 70 ordinarily used the flues are large and are open at the top of the tank. The result is that there is a very large proportion of cold air drawn up through these which either has to be heated in effecting the heat exchange, or 75 else abstracts heat from the contents of the tank. With our construction the doubling of the flue back upon itself and the discharge of the products of combustion below the burner results in a sort of a balanced column 80 arrangement that is not conducive to enforced ventilation or draft through the flue. This is especially true with a relatively long and narrow flue, such as we have shown. The rising heat, which by reason of the small 85 consumption burner is not at any time very great, is required to push this long and narrow column clear down through the return flue in order to discharge the products of combustion. The result is that the ventilation 90 through this type of flue is very slight, especially with this low consumption burner. This is very advantageous in the operation of our device for two reasons. One is that no unnecessary cold air is drawn up through the 95 flue to abstract heat. About all the air that is taken in is that which is necessary to support combustion. This form of operation has a second advantage in that it obviously delays the heated products of combustion as 100 long as possible in their movement through the long flue, and consequently the utmost of the heat units is abstracted from the products of combustion before they are discharged.

It will be obvious that if a larger cross section flue of shorter length is used that the differential in pressures tending to accelerate the movement of air and products of combustion through the flue, will be much greater. It will also be obvious that if a 105 large consumption burner is utilized that this differential in pressures which accelerates the draft will be much greater. Another important factor is that this type of flue is very advantageously suited to cooperate with the low consumption burner. In fact the burner of the consumption we have named would be out of the question with most flues, for by reason of the draft through the flues a burner of this consumption would 110 not be practical, as it would not carry enough heat to effect the necessary heat exchange under the condition obtaining in such flues. By the retardation of the ventilation in the way that we have pointed out, it is possible 115 to very effectively use a low consumption burner, such as we have described, and we find such a low consumption burner is not only desirable with such a flue by reason of lessening the necessary size of gas mains and 120 125 130

peak loads, but actually much more economical in the operation of this type of flue because it is conducive to the most sluggish circulation which is permissible in clearing the products of combustion, and thereby effects the greatest possible heat exchange.

Another valuable feature is that with a low consumption burner there is very little likelihood of scale depositing on the flues, 10 for the reason that the flues at any given point rarely reach the temperature at which scale deposits. Furthermore, with our construction with the inverted U-like flue nearly 15 all the surface is a vertical one, and consequently there is very little chance for the scale to adhere.

What we claim is:

1. A water heating apparatus of the type described, comprising an insulated storage 20 container of relatively large capacity, one or more conduits within the container for conducting the heated gases and having intake and exhaust legs extending approximately the length of the container, said intake and 25 exhaust legs being of the same size and dimensions throughout, and a single burner for the intake leg of each conduit, said burner having a relatively low fuel consumption compared to standard practice and to said 30 body of water.

2. A water heating apparatus of the storage continuous supply type, comprising in combination a storage container designed to hold a relatively large constant supply of 35 water compared to the heat units available, a conduit for conducting the heated gases having intake and exhaust legs extending approximately the full length of the container and positioned interiorly thereof, said 40 exhaust legs extending through the bottom of the container to a position below the intake to retard the flow of gases through the conduit, and an inlet conduit extending longitudinally and centrally from the top of the 45 container in close heat exchange relation with the legs of the conduit for discharging liquid to be heated at a point adjacent the bottom of the container.

3. A water heating apparatus of the type 50 described, comprising in combination a storage container designed to hold a relatively large constant supply of water compared to the heat units available, a conduit for conducting the heated gases having intake and 55 exhaust legs extending approximately the full length of the container and positioned centrally thereof, said exhaust leg extending through the bottom of the container to a position below the intake to retard the flow of 60 gases through the conduit, an inlet conduit for the discharging liquid to be heated at a point adjacent the bottom of the container, and a burner for said intake leg having a relatively low fuel consumption compared to 65 standard practice, said exhaust leg being

adapted to discharge the exhaust gases directly to the atmosphere.

4. A water heating apparatus of the type described, comprising an insulated container 70 designed to hold a relatively large supply of water compared to the heat units available, an inverted U-shaped conduit having intake and exhaust legs extending approximately the length of said container and through the bottom thereof, said conduit being of relatively small cross section throughout to retard the flow of gases to an extent just sufficient to support combustion, and a condensation trap at the bottom of said exhaust leg, whereby the gases are exhausted at a point 75 lower than the intake and directly to the atmosphere.

5. The method of heating liquids in storage tanks, which comprises confining a relatively large mass of liquid to an upright body of 80 relatively small cross section, passing heating gases derived from low consumption fluid fuel upwardly and returning the gases downwardly through the length of said body of liquid of relatively small cross section, automatically 85 controlling the rate of consumption, maintaining said body of liquid by carrying the liquid supply in close heat exchange relation with said upward and downward path of heated gases and introducing the 90 liquid supply at a point near the bottom of said mass of liquid and adjacent said controlling means, and restricting the gases in such path to a column of relatively small cross section whereby a large percentage of the 95 heat units of the gases are transferred to the liquid at the bottom of said mass of liquid, only a small percentage of the heat units transferred to the mass of liquid at the top or hottest part of the column, and substantially 100 completely transferring the remaining heat units to the liquid as the gases pass downwardly to the lower portion of said column of liquid.

6. A water heating apparatus of the 110 storage, continuous supply type, comprising an upright storage container of a relatively small cross section compared to its height, and designed to hold a relatively large constant supply of water compared to the 115 heating units available, insulating means surrounding said container to prevent radiation losses, one or more conduits within the container for conducting the heating gases having intake and exhaust legs extending approximately the length of the container, a burner for the intake leg of each conduit having a relatively low consumption compared to standard practice, said conduit having a relatively small cross section substantially 120 throughout whereby the heat units from the gases are gradually and substantially completely transferred to the water and have a relatively slow rate of movement.

7. A water heating apparatus of the 130

storage, continuous supply type, comprising a storage container, one or more conduits within the container for conducting the heated gases having intake and exhaust legs 5 extending approximately the length of the container, a single burner for the intake leg of said conduit, or conduits, having a relatively low fuel consumption compared to standard practice, said conduit having a relatively small uniform cross section substantially throughout its length, an inlet conduit extending longitudinally from the top of the container in close heat exchange relation with the legs of said conduit and terminating adjacent the bottom of said container, and a 10 thermostat element for controlling the supply of fuel to said burner, or burners, having an element projecting into the container and positioned between the two legs of the conduit and adjacent the end of said inlet conduit.

8. A water heating apparatus of the storage, continuous supply type, comprising an upright storage container of relatively small cross section and designed to hold a relatively large supply of water compared to the heat units available, insulating means surrounding said container to prevent radiation losses, one or more conduits within the container for conducting heated gases and having intake and exhaust legs extending approximately the length of the container, a burner for the intake leg of said conduit, or conduits, having relatively low fuel consumption compared to standard practice and to said body of water in said container, an inlet conduit extending longitudinally from the top in close heat exchange relation with said first named conduit and terminating adjacent the bottom of said container, means for controlling the low consumption fuel supply to said burner, or burners, positioned adjacent the end of said inlet conduit, said first named conduit having a relatively small cross section whereby the heat units from the gases, when the low consumption burner is operating, are transferred at a relatively great rate to the cold water in the lower part of the container, transferred at a relatively slow rate 40 to the hot water in the top part of the container, and the remaining heat units in the return leg of the conduit are transferred substantially completely to the said cold water in the bottom of the container, said conduit 45 of relatively small cross section and said low consumption burner co-operating to provide a relatively slow rate of movement of the gases.

9. A water heating apparatus of the storage continuous supply type, comprising a storage container of relatively small cross section compared to its height, and designed to hold a relatively large constant supply of water, inlet and outlet connections on said container for supplying and drawing off

water for current use, a conduit within the container for conducting heated gases having intake and exhaust legs extending approximately the length of the container, and a fluid fuel consuming heating element positioned adjacent the intake leg of said conduit, said heating element having a relatively low rate of fuel consumption compared to standard practice.

10. A water-heating apparatus of the storage continuous supply type, comprising a storage tank of relatively small cross section compared to its height and provided with heat insulation on its outside, and designed to hold a relatively large constant supply of water, 75 inlet and outlet connections for said tank for supplying and drawing off water for current use, a conduit within the tank of relatively small cross-section for conducting heated gases having intake and exhaust legs extending approximately the length of the tank, and a fluid-fuel consuming burner positioned under the intake leg and arranged to have when burning at its maximum a relatively low rate of fuel consumption compared with standard 80 practice.

11. A water-heating apparatus of the storage continuous supply type, comprising a storage tank of relatively small cross section compared to its height and provided with heat insulation on its outside, and designed to hold a relatively large constant supply of water, 85 inlet and outlet connections for said tank for supplying and drawing off water for current use, a conduit within the tank of relatively small cross section for conducting heated gases having intake and exhaust legs opening through the bottom portion of the tank whereby the intake and exhaust are substantially in the same horizontal plane, said legs being of a combined length substantially twice the height of the tank, and a fluid-fuel consuming burner positioned under the intake leg and arranged to have when burning at its maximum 90 a relatively low rate of fuel consumption compared to standard practice.

12. A water-heating apparatus of the storage continuous supply type, comprising a storage tank of relatively large capacity and provided with heat insulation on its outside, and designed to hold a relatively large constant supply of water compared to the heat units available, inlet and outlet connections for said tank for supplying and drawing off water for current use, a conduit within the tank of relatively small cross section for conducting heated gases, said conduit having intake and exhaust legs extending through the bottom portion of the tank whereby the intake and exhaust are substantially in the same horizontal plane and said entire conduit within the tank being of a relatively great length and at least twice the approximate height of the tank, and a fluid-fuel consuming burner positioned under the intake leg and arranged 105 110 115 120 125 130

to have when burning at its maximum a relatively low rate of fuel consumption compared with standard practice and to said body of water, the small cross section and great length of said conduit being such as to retard the flow of gases from the low consumption burner to an extent just sufficient to cause circu-

lation whereby the heat units of the gases are substantially completely transferred to the liquid.

In testimony whereof we affix our signatures.

JAMES A. BROWN.
WILLIAM J. HANDLEY.
